UNITED STATES PATENT OFFICE.

PAUL E. COOPER, OF SOMERVILLE, OHIO.

SCAFFOLD ANCHOR.

Application filed August 28, 1925. Serial No. 53,149.

To all whom it may concern:

Be it known that I, PAUL E. COOPER, a citizen of the United States, residing at Somerville, in the county of Butler and State of Ohio, have invented certain new and useful Improvements in Scaffold Anchors, of which the following is a specification.

This invention relates to a device by means of which a scaffold may be suspended from a roof and one object of the invention is to provide an anchor adapted to be mounted in firm gripping engagement with the seams of a metal roof and engaged by a hanger bar from which a scaffold is suspended.

Another object of the invention is to so mount the jaws of the anchor that they may be easily placed in position for gripping opposite sides of a roof seam and then readily forced to a gripping position and securely held.

Another object of the invention is to form the jaws with abutments adapted to extend in overlapping relation to the hanger bar of the scaffold and prevent danger of the hanger bar accidentally moving upwardly out of engagement with the anchors when in use.

Another object of the invention is to provide improved means for moving the jaws into gripping engagement with the roof seam and to so construct the jaw moving means that said means may be readily moved into or out of position to lock the jaws but not be liable to accidentally move to a releasing position.

This invention is illustrated in the accompanying drawing, wherein—

Fig. 1 is a perspective view illustrating a scaffold supported from a roof by means of the improved anchors;

Fig. 2 is a vertical sectional view taken between the jaws of one of the anchors;

Fig. 3 is a vertical sectional view through an anchor, the view being taken on the line 3—3 of Fig. 2;

Fig. 4 is a view showing the anchor in front elevation, and

Fig. 5 is a sectional view taken on the line 5—5 of Fig. 4.

When painting a barn or other building, such as shown in Fig. 1 and indicated in general by the numeral 1, it is necessary for the painter to stand upon a scaffold 2 suspended from the roof of the building. At the pres-

ent time it is customary to engage the grapples 3 of the scaffold with the ridge portion of the roof or employ auxiliary ropes which are anchored in a suitable manner to the eaves at the opposite side of the building and led over the ridge of the roof for engagement by the grapples. These methods have been found inconvenient and unsafe as it is often difficult to properly engage the grapples with the ridge of the roof or properly secure the auxiliary ropes to the eaves of the building. In order to overcome these objections, I have developed anchors which are indicated in general by the numeral 4 and are adapted to have firm gripping engagement with selected seams 5 of the roof and support a hanger bar 6 with which the grapples 3 will engage. The anchors 4 are of a duplicate construction and each formed as shown in Figs. 2 through 5.

Referring to these figures, it will be seen that each of the anchors includes jaws 7 which are formed of brass or other strong metal and are preferably triangular in shape. This provides each jaw with a wide base or lower edge portion and a forward edge 8 extending from the lower edge at right angles thereto, the jaws being of sufficient height to permit the prongs or lugs 9 to extend in overlapping relation to the upper edge face of the hanger bar 6. The hanger bar 6 is preferably a two by four and may be of any length desired. It will therefore be seen that when the anchors are put in place with the lugs extending in overlapping relation to the upper edge face of the hanger bar and the jaws firmly gripped to the seams, the hanger bar will be securely supported and cannot move upwardly and slip over the upper ends of the anchors. Toothed flanges 11 extend inwardly along the lower edges of the jaws with the teeth of one flange fitting between the teeth of the other flange, as shown in Fig. 5, and adapted to bite into the seam gripped between the jaws and very firmly hold the anchor in place. One of the jaws has also been formed with a pin or lug extension 12 adapted to engage one side of a seam and under sufficient pressure force the seam into an opening 13 formed in the companion jaw. While one lug 12 and opening 13 have been illustrated, it will be understood that others may be provided if found desirable.

The jaws are to be mounted for tilting movement towards and away from each

other and, therefore, there has been provided a pin 14 which extends between the jaws, as shown in Figs. 3 and 4, with its end portions passed through openings 15 and formed with heads 16 so that the jaws are firmly held in engagement with the pin and prevented from being forced from the ends thereof when pressure is exerted to move the lower edge portions of the jaws 5 into gripping engagement with the roof seam. The actuating device by means of which the jaws are forced to a gripping position consists of a lever handle 17 disposed between the jaws and at its inner end 10 formed with a bearing extension 18 having an opening 19 to loosely receive the pin and mount the lever or handle for swinging movement from a substantially vertical position such as shown in Fig. 4 to a horizontal position as shown in Fig. 2. A side arm 20 extends from the pivoted end of the lever and carries a wedging head 21 tapered towards one end from opposite sides, as shown in Figs. 3 and 4. From an inspection 15 of Fig. 4, it will be readily seen that when the lever is disposed vertically with the head extended beyond the forward edges 8 of the jaws the jaws may be tilted toward and away from each other upon the pin 14. 20 The upper ends of the jaws may, therefore, be moved toward each other to spread the lower end portions a sufficient distance to permit the jaws to be disposed upon opposite sides of the roof seam. When so disposed, the handle 17 is swung downwardly 25 towards the position shown in Fig. 2 and as it swings downwardly the head 21 is swung upwardly and moved inwardly between the upper end portions of the jaws. 30 As the head moves between the jaws, it exerts a cam action and serves to swing the upper end portions of the jaws apart and move the lower edges into very tight gripping engagement with the roof seam. As 35 long as the head is disposed between the upper end portions of the jaws, they cannot return to the releasing position and, therefore, there is no danger of the anchor accidentally moving out of engagement with the 40 roof seam. Beveled faces 22 are formed along the forward edges of the jaws in order to permit the wedge to be readily forced inwardly between them. 45 There has, therefore, been produced an anchor which may be easily and quickly secured to a roof and serves to very firmly support a hanger bar to be engaged by a grapple of a scaffold. At the same time the anchor may be readily released when so desired but is not liable to accidentally slip loose. 50

Having thus described the invention, I claim:

1. A scaffold anchor comprising vertically disposed coacting jaws for engagement

with opposite sides of a roof seam and adapted to support a hanger bar, fingers extending forwardly from said jaws to overlap the upper edge of the hanger bar and prevent upward movement of the bar out of engagement with the anchor, and means for moving said jaws towards each other and retaining them in tight gripping engagement with a roof seam.

2. A scaffold anchor comprising coacting jaws for engagement with opposite sides of a roof seam and adapted to support a hanger bar, a pin passed transversely through said jaws intermediate their upper and lower ends and mounting the jaws for tilting towards and away from each other, and operating means carried by said pin and adapted to engage one of the jaws and move the jaws into gripping engagement with the roof seam. 75

3. A scaffold anchor comprising coacting jaws for engagement with opposite sides of a roof seam and adapted to support a hanger bar, a pin passed transversely through said jaws intermediate their upper and lower ends and mounting the jaws for tilting towards and away from each other, and operating means mounted between said jaws and including means to force their upper end portions away from each other and cause their lower edge portions to be moved into tight gripping engagement with the roof seam. 80

4. A scaffold anchor comprising coacting jaws for engagement with opposite sides of a roof seam and adapted to support a hanger bar, a pin passed transversely through said jaws intermediate their upper and lower ends and mounting the jaws for tilting towards and away from each other, and operating means pivotally mounted upon said pin between the jaws and including a cam portion adapted to be forced between the upper portions of the jaws and tilt the jaws longitudinally of the pin to move their lower edge portions towards each other for tight gripping engagement with the roof seam. 100

5. A scaffold anchor comprising coacting jaws for engagement with opposite sides of a roof seam and adapted to support a hanger bar, a pin passed transversely through said jaws intermediate their upper and lower ends and mounting the jaws for tilting towards and away from each other, operating means including a handle portion pivotally mounted at one end upon said pin between the jaws and extending outward from the jaws, a side arm extending from the pivoted end of said handle and of a length to extend beyond the forward edges of the jaws when the handle is disposed upwardly, and a wedging head at the outer end of said side arm adapted to be forced inwardly between the upper portions of the jaws when the han- 110

dle is swung downwardly and tilt the jaws to move their lower edge portions into tight gripping engagement with the roof seam.

6. A scaffold anchor comprising coacting jaws for engagement with opposite sides of a roof seam, a pin pivotally mounting the jaws for tilting towards and away from each other into and out of a gripping position, and an operating member carried by said pin between the jaws and including means for engaging one of the jaws and moving the jaws to a gripping position.

7. A scaffold anchor comprising coacting jaws for engagement with opposite sides of a roof seam, a pin pivotally mounting the jaws for tilting towards and away from each other into and out of a gripping position, and an actuating member carried by said pin and adapted to engage one of the jaws and move the jaws to a gripping position.

In testimony whereof I affix my signature.

PAUL E. COOPER. [L.S.]
